(57) **CLAIM**

The ornamental design for a webcam, as shown and described.

DESCRIPTION

FIG. 1 is a perspective view of a webcam showing my new design and having an upper casing in a rotating state with respect to a bottom casing thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an alternate perspective view of the webcam shown in a non-rotating state.

The broken line portion in FIGS. 1-4 and 6-8 is shown to illustrate environment only and form no part of the claimed design.
